UNITED STATES PATENT OFFICE.

ERNEST EMILE HERMANN HEINRICH, OF BRUSSELS, BELGIUM.

HANGER FOR TROUSERS OR GOWNS.

SPECIFICATION forming part of Letters Patent No. 674,556, dated May 21, 1901.

Application filed November 13, 1900. Serial No. 36,359. (No model.)

To all whom it may concern:

Be it known that I, ERNEST EMILE HERMANN HEINRICH, a citizen of Germany, residing at 2 Rue Gillon, Brussels, in the Kingdom of Belgium, have invented new and useful Improvements in Hangers for Trousers or Gowns; and I do hereby declare the following to be a full, clear, and exact description of the same.

10 This invention relates to hangers for trousers and gowns, &c.; and the object of the invention is to provide a simple and efficient device of this nature adapted to clasp and thus sustain the garment by virtue of the latter's own weight.

In the accompanying drawings, wherein corresponding letters of reference indicate like parts, Figure 1 is a perspective view of my improved garment-hanger. Fig. 2 is a 20 view showing the device open ready to receive the garment. Fig. 3 shows the device in operative position suspending a pair of trousers, and Fig. 4 is a view in side elevation of the device as seen in Fig. 2, dotted lines being used to show the positions of the parts when closed.

In said drawings, *a* and *b* designate two plates or strips, preferably formed of wood, between which the garment, either the bottoms 30 of the trousers or the waistband of the skirt, is adapted to be clasped. It is preferable that each of these plates or strips be protected with a covering of velvet, plush, or other suitable material *c*. Near their ends the plates or strips are provided with corresponding holes *d* *e*. These openings are placed as near the ends of the plates or strips as possible, so as to leave the maximum space between them for the accommodation of the garment.

40 *f* designates a pair of cords, each of which is passed through the corresponding holes *d* in the plates or strips at one end thereof, and

preferably the corresponding holes *e* at the other ends of said plates or strips. At the corresponding ends of the strips these cords 45 extend through them from opposite directions, their ends being knotted, so as to prevent them from pulling through the holes, as best seen in Fig. 1.

In using the device the strips are first laid 50 flat, with their inner faces upward. The bottoms of the trousers or the waistband of the skirt is then laid over one of the plates or strips, whereupon the other is placed over the garment and the cords drawn up taut. By 55 virtue of the weight of the garment the latter may be now suspended, care being taken that the plates or strips well clasp the garment before the whole is hung up.

g is simply a hook which may be used to 60 immediately engage the cords when the device is suspended.

Having thus fully described my invention, what I claim as new, and desire to secure by Letters Patent, is—

65 The combination of a pair of elongated plates or boards each having an opening near each of its ends, and a pair of slack cords, the ends of one cord being respectively extended through the openings of one plate or board 70 toward the other plate or board and secured to the latter, and the ends of the other cord being in turn respectively extended through the openings of said other plate or board toward said first-named plate or board and secured 75 to the latter, substantially as described.

In testimony whereof I have signed this specification in the presence of two subscribing witnesses.

ERNEST EMILE HERMANN HEINRICH.
